UNITED STATES PATENT OFFICE.

ELIHU C. GRACE, OF MOBILE, ALABAMA.

BOTTLE REFRIGERATOR.

Application filed March 20, 1924. Serial No. 700,689.

To all whom it may concern:

Be it known that I, ELIHU C. GRACE, a citizen of the United States, residing at Mobile, in the county of Mobile and State 5 of Alabama, have invented certain new and useful Improvements in Bottle Refrigerators; and I do hereby declare the following to be a full, clear, and exact description of the invention, such as will enable others 10 skilled in the art to which it appertains to make and use the same.

This invention relates to bottle refrigerators, and has for its object to improve the construction of the bottle holding tubes 15 heretofore proposed.

With these and other objects in view the invention consists in the novel details of construction and combinations of parts more fully hereinafter disclosed and particularly 20 pointed out in the claims.

Referring to the accompanying drawings forming a part of this specification, in which like numerals designate like parts in all the views:

25 Figure 1 is a top plan view of a device made in accordance with this invention;

Figure 2 is a longitudinal sectional view taken on the line 2—2 of Figure 1, looking in the direction of the arrows;

30 Figure 3 is a transverse sectional view taken on the line 3—3 of Figure 1, looking in the direction of the arrows;

Figure 4 is a fragmentary plan view of a detail of construction illustrating a method 35 of supporting the inner tank member of this device;

Figure 5 is a sectional view taken on the line 5—5 of Figure 4, looking in the direction of the arrows;

40 Figure 6 is a fragmentary perspective view showing the end construction of the inner tank member.

Figure 7 is a fragmentary longitudinal sectional view similar to Figure 2 illustrating 45 a modification in construction; and

Figure 8 is a fragmentary transverse sectional view similar to Figure 3 illustrating the modification shown in Figure 7.

In order that the precise invention may 50 be the more clearly understood it is said:— In the Reissue Patent #15,482, granted October 31, 1922, to Soutullo, and of which I am one of the assignees of record, there is disclosed a refrigerator, provided with a 55 plurality of individual U-shaped tubes, numbered 17 and 45 in said patent, and

adapted to receive bottles as there disclosed. But in attempting to manufacture these refrigerators, it was discovered that the cost of making these said tubes was so excessive 60 as to be commercially impracticable. In fact, a little consideration will show that the only practical commercial way of making round thin metal tubes of the size of 65 bottles, such as those indicated at 45 in the above mentioned patent, is to make them in straight forms. But when such straight formed tubes are thus made and then bent circularly into U-shaped formations, it is 70 evident that the metal wall, along the concave section of the bent thin metal tube, will buckle, and form ridges which extend inwardly, thereby so constricting the internal passageway of the tube as to cause the bottles to bind when placed therein. 75

It was further found impracticable and too costly to make the tubes from sectional pieces of metal as illustrated at 17 in said patent.

According to the present invention, on 80 the other hand, I avoid the foregoing objections, and produce a commercial, practical, refrigerator by providing the tubular structure now to be disclosed. Referring to the drawings, 1 indicates an outer wall of a refrigerator box, and 2 an inner wall so positioned as to form the air space 3 therebetween, serving to exclude heat and maintain 85 the box at a low temperature within, all in the manner well known.

4 represents the bottom of the box which may have attached thereto any suitable supporting means 5. If desired an inner bottom 6 of heat insulating material may be provided, all as will be clear from Figures 90 2 and 3. Instead of providing the refrigerator with individual bottle tubes, as in the reissue patent above mentioned, according to 95 this invention, I provide an inner corrugated sheet of metal 11 having its corrugations running longitudinally thereof, and bend it into a U-shaped form, as indicated in Figures 3 and 6. The side edges of this U-shaped sheet 11 are next secured to end pieces 18, thus forming an inner tank adapted 100 to form cooling chambers. Outside this said inner tank I provide a second and similarly corrugated sheet 10, which is likewise bent into a U-shaped form, and of such dimensions as will snugly fit the interior of 110 the refrigerator casing. That is to say, the outwardly extending portions 12 of the

corrugations in sheet 10 rest against the sides and bottom of the refrigerator as illustrated, while the inwardly extending portions 13 of the corrugations of the sheet 10 extend inwardly from said walls or bottom of the refrigerator a distance approximately equal to one half of the diameter of the tubes 15 to be formed. The inwardly extending portions 14 of the corrugations 10 in the sheet 11 are of such dimensions as to form the other half of the tubes 15 while the outwardly extending portions 16 of the corrugations in the sheet 11 are of such dimensions that they substantially meet the corrugated portions 13 in the sheet 10. The edges of the outer sheet 10 are likewise closed by flat end pieces 17 similar to the members 18, and thus is an outer tank 30 formed into which fits the inner tank 31, as 20 will be clear from the drawings.

The two tanks 30 and 31 being thus nested together, form a plurality of tubes 15 into which bottles 19 may be placed, as indicated. The end edges 20 of each sheet 10 and 11 25 may be crimped or otherwise attached to the edges 21 of the end plates 17 and 18, as by the joints 22, such as are best illustrated in Figure 4. Further, the upper horizontal edges of the sheet 18 is provided with an extension 23 which is turned over to form the tubular portions 24 best shown in Figure 5, through which pass the supporting rods 25 having the turned down ends 26 only one of which is shown in the drawings. The 30 end sheets 17 have secured thereto as by the means 27 the angle supporting plates 28 on which the tubular extensions 24 rest and over the ends of which the turned down portions 26 of the rods 25 extend thereby positioning the inner tank 31.

32 and 33 represent any suitable refrigerating compartment and 34 represents a cooling medium such as brine occupying the space between the nested tanks 30 and 31, 45 as well as the bottle tubes 15, thus cooling the bottles while partially supporting or buoying up the same. This latter action reduces friction and renders it practicable to use a bottle at one end of a tube 15 to 50 push out another bottle at the other end of said tube.

That is, a construction of this kind forces or reminds the attendant to always put a warm bottle into a tube 15 when he desires to serve a cold bottle therefrom, and it insures the customer always getting the coldest bottle that is in the tube. The plurality of tubes enables the proprietor to keep on hand and to readily serve a 60 great variety of different drinks.

The angle 28 and its coating parts not only prevents the inner tank from shifting its position but renders it possible to readily remove the inner tank for cleaning and 65 other purposes. It is an important feature

of this invention that the removal of the inner tank not only renders the cleaning of the tubes 15 easy but it splits said tubes in halves and thus enables the attendant to readily remove any broken bottles, or any 70 whole bottle that may from any cause stick in said tubes. Said angle bar 28 and rod 25 it will be seen also serve to position the inner tank 31 relative to the outer tank 30 in such manner to properly form the 75 tubes 15.

In Figures 7 and 8 is illustrated a modification of the construction just described wherein a plurality of tanks such as three is provided to form a double row of bottle 80 tubes. That is to say, there is provided an outer tank formed by a U shaped corrugated sheet 120 having plane end members 170. Within this outer tank is provided a second tank likewise formed by a U shaped corrugated sheet 110 having plane end members 180 and adapted to so fit within said outer tank that the corrugations of the one 85 will form with the corrugations of the other a series of tubular passageways through which bottles may pass, all so far as has been heretofore disclosed.

A third tank likewise formed by a U shaped corrugated sheet 130 having plane end members 190 and similar in all respects 90 to the second tank except as to size, is disposed within said second tank in such a manner that the corrugations of the third tank will form with the corrugations of the second tank a series of tubular passageways 100 adjacent the aforementioned series of passageways. This third or innermost tank may be supported in and spaced from the second or intermediate tank in a manner similar to that employed in supporting and 105 spacing the intermediate tank, or in any other suitable way, the particular method not being illustrated in the accompanying figures.

It is obvious that those skilled in the art 110 may vary the details of construction as well as the arrangement of parts without departing from the spirit of the invention and therefore I do not wish to be limited to the above disclosure except as may be required by the claims.

What is claimed is:

1. A bottle refrigerator comprising a chamber provided with a pair of transversely corrugated tanks spaced from each other and so disposed one inside the other with their corrugated portions so opposed as to form a plurality of U-shaped tubes adapted to receive curved rows of bottles. 120

2. A bottle refrigerator comprising a 125 chamber provided with a pair of tanks having transversely corrugated U-shaped walls disposed one inside the other with their corrugated portions so opposed as to form a plurality of U-shaped tubes adapted to re- 130

ceive curved rows of bottles and also a fluid to buoy up said bottles.

3. A bottle refrigerator comprising a chamber provided with a pair of corrugated tanks disposed one inside the other, one of which is readily removable from the other, said tanks having their corrugated portions so opposed as to form a plurality of U-shaped tubes adapted to receive curved rows of bottles.

4. A bottle refrigerator comprising a chamber provided with a pair of transversely corrugated tanks spaced from each other and so disposed one inside the other with their corrugated portions so opposed as to form a plurality of U-shaped tubes adapted to receive curved rows of bottles, the inner one of said tanks being readily removable from the outer and spaced therefrom to form a liquid holding chamber.

5. A bottle refrigerator comprising a chamber provided with a pair of transversely corrugated tanks spaced from each other and so disposed one inside the other with their corrugated portions so opposed as to form a plurality of U-shaped tubes adapted to receive curved rows of bottles, the

outer tank being provided with a supporting means for the inner tank.

6. A bottle refrigerator comprising a chamber provided with a pair of transversely corrugated tanks spaced from each other and so disposed one inside the other with their corrugated portions so opposed as to form a plurality of U-shaped tubes adapted to receive curved rows of bottles, said tanks being associated with means for properly positioning said corrugated portions forming said tubes.

7. A bottle refrigerator comprising a chamber provided with a plurality of nested transversely corrugated tanks each tank so spaced and so disposed one inside the other that the corrugations of said tanks will form a plurality of longitudinally disposed rows of passageways adapted to receive curved rows of bottles and a fluid to buoy up said bottles each row of passageways being of U-shaped cross section and means located within the innermost tank for cooling said fluid and bottles.

In testimony whereof I affix my signature.

ELIHU C. GRACE.
